Primary Examiner — Lucy Lieberman(74) *Attorney, Agent, or Firm* — Kalow & Springut LLP(57) **CLAIM**

The ornamental design for a watch dial, as shown and described.

DESCRIPTION

The sole view is a front view of a watch dial embodying my claimed design.

The broken lines in the drawing are used to show portions of the watch dial that do not form part of the claimed design. The claimed portions of the front of the watch dial are flat and are on the same plane.
